UNITED STATES PATENT OFFICE

ALBERT B. COLLINGBOURNE, OF ELGIN, ILLINOIS, ASSIGNOR TO COLLINGBOURNE MILLS, INC., OF ELGIN, ILLINOIS, A CORPORATION OF ILLINOIS

DISPLAY DEVICE

Application filed May 3, 1929. Serial No. 360,285.

This invention relates to display devices, and as shown and described is embodied in a device for displaying a dental floss container.

5 The device is exceedingly simple, easy to assemble and effective for its intended purpose. It comprises a blank or card of relatively stiff material, such as cardboard, upon which advertising matter may appear, having a continuous flexible band, preferably of elastic material, associated with the card for holding thereon the article to be displayed.

In the drawings:—

10 Figure 1 is a front view of a display device embodying my invention.

Figure 2 is a rear view of the same.

15 In that embodiment of my invention shown in the drawings, the display device comprises a relatively stiff blank made of cardboard, 20 rectangular in shape, as indicated at 10. Apertures 11 are punched through the card 10, in this instance in its lower right hand corner, leaving space for advertising matter indicated on the front face of the card. A 25 continuous band, preferably an elastic band, is associated with the card, having its laps 12 arranged adjacent the rear surface 13 of the card and its two end loops 14 extending forwardly through the respective apertures 11 30 and protruding from the front surface of the card 10.

35 A dental floss container 15 or other article to be displayed is inserted in the loops 14 of the band and is held detachably, but securely, against the face of the card 10.

I claim as my invention:—

40 A display device for elongated relatively stiff articles consisting of a supporting blank of relatively weak material provided with two apertures spaced apart a substantial distance and having a continuous elastic band associated therewith, the band being threaded through the apertures from the rear surface of the blank so that the loops protrude 45 at the front surface through the respective apertures, the elastic band portions intermediate the loops lying closely side by side in parallel relation against the back of the blank between the apertures, the article to be displayed being inserted through said loops and

held thereby against the face of the blank which is compressed between the relatively stiff article and the parallel band portions, thereby strengthening the blank between the apertures and preventing tearing of the material.

45 In testimony, that I claim the foregoing as my invention, I affix my signature, this twenty-ninth day of April, 1929.

ALBERT B. COLLINGBOURNE.
